HAND PUMP FOR GREASES, ETC.

Warren P. Valentine, Line Lexington, Pa., assignor to National Transit Pump & Machine Company, Oil City, Pa., a corporation of Pennsylvania

Application September 28, 1931
Serial No. 565,677

10 Claims. (Cl. 221—80)

The invention relates to a pump, for delivering grease, oil or the like, herein conventionally called "grease", usually to different parts of automobiles or similar mechanisms, and with more 5 particular reference to a rotary hand pump of the character indicated.

One purpose of the invention is to provide a pump of the character indicated, adapted to easy and inexpensive manufacture and well suited 10 to the needs of service.

A further purpose is to rigidly mount a grease delivery pump on a support adapted to function as a lid of a commercial grease container, and adapted to replace the normal lid of the container during the use of the container by a customer as a source of grease.

A further purpose is to provide a ball ratchet connection between an operating shaft and the operating handle of a grease delivery pump, 20 which is mounted upon a grease container, permitting the handle to be set at any angle with respect to the shaft before operating the pump.

A further purpose is to locate the operating shaft of an eccentric rotor pump element inside 25 a grease discharge pipe from the pump and to locate the pump at the bottom of a container which is to be emptied.

A further purpose is to provide a pump of the character indicated for easy mounting upon the 30 different commercial grease containers, with the rotor element of the pump normally submerged in grease, and inside and near the bottom of the container.

A further purpose is to mount a rotor element 35 of a pump of the character indicated upon an adjustably telescoping drive shaft and inside an adjustably telescoping discharge tube from the pump element, permitting an easy adjustment of the position of the pump element with respect to 40 a housing of pump operating mechanism, and thereby adapting the pump to readily cooperate with grease containers of different depths, said housing being desirably mounted on a cover interchangeably carried by the different containers.

A further purpose is to admit the discharge 45 pressure to the rear faces of the blades of a rotor pump element of the character indicated, preferably also spring pressing the blades outwardly.

50 A further purpose is to mount a meter element upon the outlet side of a housing member which forms part of an oil delivery conduit, and a rotor pump element upon the inlet side thereof at the lower end of a discharge tube from the pump ele-

Further purposes will appear in the specification and in the claims.

I have elected to illustrate one only of the different forms of my invention, showing however a modification with respect to details and selecting a main form and a modification thereof that are practical and efficient in operation and which well illustrate the principles involved.

Figure 1 is a longitudinal sectional elevation illustrating structure embodying a desirable form 55 of my invention, mounted upon a grease container.

Figure 2 is a right-side elevation of a portion of Figure 1.

Figures 3, 4, 5, 6, 7 and 8 are detail sections 70 taken upon the lines 3—3, 4—4, 5—5, 6—6, 7—7, and 8—8 respectively of Figure 1, looking in the directions of the corresponding arrows.

Figure 9 is a fragmentary section corresponding to a portion of Figure 1 showing a lid member 75 with an opening that is closed, with pump mechanism in Figure 1 closed by a normal cover in Figure 9.

Figure 10 is a side elevation of a pump structure, similar to that of Figure 1 but modified with respect to details.

Figure 11 is a right side elevation of Figure 10.

Figure 12 is a longitudinal vertical section of Figure 10 taken on the line 12—12 thereof looking in the direction of the arrows.

Like numerals refer to like parts in all figures.

Describing in illustration and not in limitation and referring to the drawings:—

The rotary pump is intended to be used on, and as a unit with the tops or covers of commercial grease containers, the pump mechanism being mounted interchangeably on different containers optionally to be shifted from one container to another when the one container becomes empty.

In Figure 1 the pump mechanism 15 is rigidly mounted upon a support 16 that functions as a lid for a grease container 17, and is preferably for interchangeable use on different commercial containers.

The lids of the commercial grease containers may be provided each with an opening 18 (Figure 9) normally closed by a cover 19, the opening 18 being of size to adapt the pump mechanism 15 to be mounted on the lid interchangeably with the cover. More usually the same lid may support the pump mechanism upon any number of successive containers while temporarily replacing the normal lids thereof.

A central housing 20 of the pump mechanism 110

has a downwardly directed grease inlet 21, a discharge outlet 22 and a shaft opening 23.

The grease inlet 21 is flanged at 24 so that it may be secured to the top surface of the lid 16, 5 and carries a downwardly extending tube 25 that supports and forms an upward discharge tube for a rotor pump located near the bottom of the container.

As illustrated the tube 25 fits within the inlet 10 21 and is welded inside the bore of a ring 26. The latter is attached to flange 24 by screws 27 and the flange 24 is fastened to the cover by screws 16'.

The pipe 25 thus rigidly connects at its upper 15 end into the inlet of the housing and an adjustment is provided to fit different depths of cans, permitting variation of the distance between the housing and rotor pump at the lower end. The pipe 25 between the pump element and housing inlet is longitudinally telescopic with respect to the discharge connection from the rotor pump. This connection includes a pipe 28 that is rigidly connected to the discharge end of the body 29 of the rotor pump and upwardly closely fits over 25 and is adapted to telescope along the lower portion of the pipe 25.

The pipe 28 fastens at its lower end into the bore of a flange or gland 30 which is in turn rigidly fastened to the discharge end of the body 30 29 of the rotor pump. Studs 31 are screwed at their lower ends into the body of the pump, passing through perforations of the lower gland 30 and nuts 32 on these studs clamp the gland to the body.

35 The studs 31 extend upwardly on opposite sides of the pipe 28 through a binding gland 33 at the upper end of the pipe 28 and when this gland 33 is tightened downwardly upon the upper end of the pipe 28 by suitable nuts 34 on the upper 40 threaded ends of the studs the inner annular wedge surface 35 of the binding gland tightly compresses the upper end of the pipe 28 on to the outside of the pipe 25, and holds the pipes 25 and 28 as a unit.

45 The rotor pump includes a hollow body 29 having preferably a circular interior, and a rotor element 36 inside the body with ends sealing against the body and provided with blades 37 movable inwardly and outwardly in diagonal 50 slots 38. The blades 37 are shown spring pressed at 39 to maintain continuous sealing engagement at their outer edges with the interior of the body.

The rotor element 36 is fixedly mounted upon a shaft 40 which has bearing support at 41 in 55 a bottom plate 42 of the body, and a bearing support at the upper end of the rotor in a sleeve 43 carried by the upper end wall of the body.

The body 29 is provided with an inlet port at 44 and an outlet port at 45 to a delivery chamber 60 46 that discharges upwardly into the telescoping pipes.

The upper end of the rotor shaft is squared at 47 to fit inside the lower end of a square driving tube 48 to which it is pinned at 49. The upper 65 end of the driving tube 48 receives a downwardly projecting square drive shaft 50 that makes a sliding fit with the square interior of the drive tube 48 and at its upper end carries a bevel pinion 51 which meshes with a bevel gear 52 upon 70 an inner end of an operating shaft 53 passing through the shaft opening of the housing.

The operating shaft 53 passes outwardly through a stuffing box 54 and a packing gland 55, and carries a handle 56 for operating the pump.

75 The operating connection between the crank

handle 56 and shaft 53 desirably includes a ball-ratchet mechanism which adapts the crank handle to be set to any angular position without affecting the pump, and then to be operated through any and very small ranges of angular movement, a feature of the invention that is sometimes particularly desirable when operating clearances are small, or when a small quantity or a very accurate amount of lubricant is required to be delivered.

80 As illustrated in Figure 7, ratchet balls 57 loosely fit bores 58 within the hub of the crank handle and are pressed to ratchet engagement with the shaft by springs 59 held to their duty by suitable screws 60 in the outer ends of the bores 58.

85 The square shaft 50 carries an externally circular sleeve 61 adjacent the pinion 51 (see Figure 3), the sleeve 61 journaling the shaft in a bearing 62 longitudinally ported at 63 to provide conduit connection between the interior of the 90 pipe 25 and the interior of the housing.

95 The blades 37 of the rotor are illustrated as resiliently pressed outwardly in their slots by springs 39. These springs are seated at their inner ends in suitable bores or recesses 64 in the 100 rotor, and at their outer ends against the ends 65 of the blades (Figure 5).

105 Pressure connection is provided between the interior edges of the blades and the discharge side of the pump. As illustrated the interior of the body is circularly grooved upwardly at 66 in position to register with the slots 38 inwardly of the blades 37 and suitable holes 67 connect these grooves with the delivery chamber 46 at the upper end of the pump.

110 The housing 20 finds outlet through a flexible grease delivery connection 68 shown, which may terminate in a spring-controlled delivery nozzle. The flexible connection 68 may connect into the housing from a lateral opening 69 as illustrated 115 in Figures 10 and 11 or may lead from the discharge side of a meter as indicated in Figures 1 and 2.

120 The housing 20 has an opening 70 large enough to pass the bevel gear 52. In the form of Figures 1 and 2 this opening is a discharge opening to a meter 71 with a filter or screen 72 preferably placed over the opening 70 and ahead of the meter.

125 As illustrated, the meter element is located inside a casing 73 and as this meter element is not in itself a portion of the present invention except in combination with the other parts of the invention it is believed to be unnecessary to describe it in any considerable detail.

130 A rotary inclined disc type of meter is shown with inlet at 74 and delivery at 75. The rotary oscillation of the disc by reason of the passage of the grease from the inlet at 74 to the outlet at 75 effects a rotation of a shaft 76, which operates through suitable gearing 77, an indicator 78 and/or an integrator 79 showing the delivery of grease through the meter.

135 Preferably the housing 20 is firmly but removably fastened to the container 17 at the flange 24 and a suitable projecting handle 80 is provided for carrying the pump and container as a unit to the location at which the grease is to be used.

140 The longitudinally adjustable connection between the rotor pump and the housing permits the pump to be placed substantially in the bottom of any commercial container, irrespective of variant depths of the container.

145 If desired the container may be recharged with 150

grease, or when empty, the pump unit may be transferred to another container with or without a transfer of the supporting lid.

In some cases the containers to be fitted may 5 all be of the same depth. In this event, the tube 25 between the pump element and the housing and likewise the shaft 50 will be non-adjustable, in that the added expense of making these connections adjustable will then be unnecessary.

10 This is seen in Figures 10, 11 and 12.

It will be understood that the auxiliary meter, shown in Figures 1 and 2 may also be dispensed with in that a user may approximately determine the amount of delivery of grease by the 15 number of rotations of the operating shaft 53. In this event, the opening 70 may be closed by a tight cover plate 81, as best seen in Figures 11 and 12, the flexible connection to the housing being indicated at 68.

20 In the form of Figures 10 and 11 the adjustment of the height has been omitted and a flange 82 at the lower end of the pipe 25 is bolted to the top of the pump body, as by bolts or studs 83.

In either type of mechanism the pump is desirably supported on the grease container, with the 25 container and pump mechanism suitably handled as a unit.

In operation of the form of Figures 1 to 9, the 30 depth of the container 17 is first ascertained and the relationship of the pump to the flange 24 is adjusted and the pump is then locked in the adjusted position, so that, when positioned, the pump will be located close to the bottom of the container. The cover cap 19 is then removed from a can filled with grease, and the pump end 35 29 of the unit 15 is inserted through the opening, and forced down into the grease until the flange 24 rests upon the top 16. Screws are then placed about the flange and screwed into the top 16 to 40 hold the unit rigidly in place and at the same time seal the opening 18.

With the unit thus secured, a few turns of the 45 crank handle 56 are now made in order to force the content upward through the tube 25, and into the meter, so that the meter will be ready to indicate as soon as grease starts outward through the delivery pipe 68.

The turning of the crank 56 imparts motion 50 to the shaft 53 through the ball ratchet mechanism illustrated in Figure 7, causing the bevel gear 52 and pinion 51 to move and rotate the square shaft 50 and thence the square tube 48, to which the pump rotor 36 is attached.

The rotor, being eccentric within its casing 29, 55 creates a crescent shaped opening (when viewed in sectional plan) and the rotor blades 37 as they advance are successively and gradually forced outward by the action of springs 39, assisted by the pump pressure admitted through the openings 67, against the wall of the casing 29. The blades 37 travel into this crescent opening, following the casing wall until they are forced back into the rotor again against the expansion of the 60 springs 39.

65 The result of this action of the rotor within the pump is to create a succession of pockets gradually increasing in area, and then as the rotor turns to gradually decrease the area of the same pockets. The start of the formation of the 70 pockets is opposite the opening 44 in the outer casing 29 of the pump, resulting in a quantity of grease being drawn into the beginning of the crescent by the action of the rotor as it passes the opening.

75 The grease is then carried forward until the

pocket begins to decrease in area, at which time the blades have come into registry with the opening 45 in the top of the casing, and the grease within the gradually decreasing area is forced upward through the opening 46, up the 80 tube 25, through the ports 63 and into the housing 20.

Each pocket formed by the eccentric rotor, the 85 rotor blades and the concentric casing, collects its quota of grease and gradually forces it upwardly through the opening above. The rapid succession of these actions causes a continuous flow of the grease, which follows the tube 25 to the housing 20, through the meter 71 and thence to its final outlet through the flexible connection 90 68.

When the pump has collected and delivered all the content which will flow to it, the screws in the flange 24 are taken out and the unit 15 is removed to a filled can.

In the design of the pump shown in Figures 10, 11 and 12, no preliminary adjusting is necessary, this pump being designed to fit a can of predetermined size. Otherwise the operation of the pump itself is identical with that just described, 100 only that the grease is passed directly from the casing 20 to the flexible delivery pipe 68—there being no meter present.

In view of my invention and disclosure variations and modifications to meet individual whim 105 or particular need will doubtless become evident to others skilled in the art, to obtain all or part of the benefits of my invention without copying the structure shown, and I, therefore, claim all such in so far as they fall within the reasonable 110 spirit and scope of my invention.

Having thus described my invention, what I claim as new and desire to secure by Letters Patent is:—

1. In a grease pump of the character indicated, 115 a housing having a grease inlet and a grease outlet, an inlet tube connected at its outlet end into the said grease inlet, an operating shaft of non-circular section having an intermediate portion in the said grease inlet, bearings for the 120 shaft at the housing end providing grease passage between the shaft and the bearings, a rotor pump mounted on the inlet end of the tube discharging into the tube and a drive shaft for the rotor pump having an upper non-circular portion 125 fitting the non-circular section of the operating shaft, said drive shaft comprising operative connection between the pump and shaft through the tube.

2. In a grease pump of the character indicated, 130 a housing having a grease inlet, a grease outlet and a shaft inlet, a telescopic inlet tube connected at its outlet end into the grease inlet, an operating shaft having an intermediate portion in the shaft inlet, a rotor pump mounted on the 135 inlet end of the tube discharging into the tube and operative connection between the pump and shaft having a telescope portion inside the tube.

3. In a grease pump of the character indicated, 140 a housing having a grease inlet, a grease outlet and a shaft inlet, an inlet tube connected at its outlet end into the grease inlet, a second tube telescoping over the lower portion of the first, a clamp holding the tubes in adjusted telescoped position, an operating shaft having an intermediate portion in the shaft inlet, a rotor pump mounted on and discharging into the lower end of the second tube and operative connection between the pump and shaft having a telescope 145 portion inside the tubes.

4. In a grease pump of the character indicated, a housing having a grease inlet, a grease outlet and a shaft inlet, an inlet tube connected at its outlet end into the grease inlet, a second tube telescoping over the lower portion of the first, an operating shaft having an intermediate portion in the shaft inlet, a rotor pump mounted on and discharging into the lower end of the second tube, operative connection between the pump and shaft having a telescope portion inside the tubes, and a binding clamp adjustably compressing an upper portion of the second tube on to the first tube. 80
5. A lid for interchangeable use upon a plurality of grease containers, a pipe of adjustable length having an upper portion rigidly connected to the lid, a rotor pump beneath the lid on the lower end of the pipe, connection for the pump having longitudinal adjustment, a discharge fitting having an inlet receiving the upper end of the pipe, and operating mechanism of the rotor inside the fitting and pipe and including non-circular slidingly engageable members connecting for driving purposes and longitudinally adjustable. 85
6. A hand grease pump adapted for insertion into grease cans of variant depth, comprising an operating mechanism intended to lie outside of the can and terminating at its lower end in an upper pipe and rotary shaft of non-circular section, a lower pipe into which the upper pipe telescopes to make a discharge conduit system through the pipes, a grease pumping unit with which the lower pipe connects and which is adapted to lie at the bottom of the can and a driving connection between the operating member of the pumping unit and the shaft of non-circular section within which the shaft is telescopically movable and which is rotated by said shaft. 90
7. In a grease pump, a hand-pumping element including a shaft and a gear turned by the shaft, a pump operating shaft, a gear at the upper end thereof engaging the first gear, a casing surrounding the gears, a discharge pipe for the grease leading into the casing and surrounding the pump operating shaft, a bearing for the pump operating shaft within the discharge pipe affording grease discharge passage between the bearing and the shaft and also between the bearing and the pipe, a pumping unit including a body and a rotor and connections from the discharge pipe and pump operating shaft respectively to the pump body and rotor of the pumping unit whereby the pumping unit discharges from the casing through the pipe and through the passages inside and outside the bearing. 95
8. A pumping unit for use upon grease containers of variant depth, comprising a hand-operating mechanism adapted to be located outside of the container, a cover adapted interchangeably to fit upon the tops of the different containers and rigidly united to the hand-operating unit to provide for transfer of the hand-operating unit and cover from container to container, a rotary pump adapted to fit into and lie near the bottom of the containers of different depths and telescoping connections between the hand-operating mechanism and the pump for operating the pump and other telescoping connections surrounding the first for carrying the discharge therefrom out through the cover. 100
9. In a hand pump for pumping grease out of containers of variant height, a pump body, a pump rotor therein, a discharge pipe of adjustable length connected with the body, a cover through which the discharge pipe passes and to which it is rigidly attached, the cover being removable from the container and adapted for use on different containers, a driving shaft for the rotor passing through the cover and having a non-circular section through a portion of its length and a corresponding surrounding section through another portion of its length providing telescopic adjustability of the length of the driving shaft, a casing to which the discharge pipe is connected, an outlet pipe from said casing, gearing in the casing connected to the drive shaft and hand-operating means for turning the gearing. 105
10. In a hand pump for pumping grease out of containers of variant height, a pump body, a pump rotor therein, a discharge pipe of adjustable length connected with the body, a cover through which the discharge pipe passes and to which it is rigidly attached, the cover being removable from the container and adapted for use on different containers, a driving shaft for the rotor passing through the cover and having a non-circular section through a portion of its length and a corresponding surrounding section through another portion of its length providing telescopic adjustability of the length of the driving shaft, a casing to which the discharge pipe is connected, an outlet pipe from said casing, hand-operating means for turning the driving shaft, connections from the hand-operating means to the driving shaft and a ball clutch in the connections. 110
- WARREN P. VALENTINE. 130
